(57) **CLAIM**

The ornamental design for a current inverter as shown and described.

DESCRIPTION

FIG. 1 is a first side elevation view of a current inverter showing the new design;

FIG. 2 is a second side elevation view thereof;

FIG. 3 is a top perspective view thereof;

FIG. 4 is a top plan view thereof;

FIG. 5 is a front side view thereof;

FIG. 6 is a back side view thereof;

FIG. 7 is a bottom plan view thereof; and

FIG. 8 is a bottom perspective view thereof.

FIG. 9 is a back elevation view of a second embodiment of

a current inverter showing the new design;

FIG. 10 is a top perspective view thereof;

FIG. 11 is a bottom plan view thereof;

FIG. 12 is a first side elevation view thereof;

FIG. 13 is a second side elevation view thereof;

FIG. 14 is a top plan view thereof;

FIG. 15 is a front elevation view thereof; and,

FIG. 16 is a bottom perspective view thereof.

In the drawings, the broken lines depict a portion of the current inverter, which form no part of the claim.

1 Claim, 16 Drawing Sheets
